DESIGN FOR A PORTABLE COOLING SYSTEM CLEANING DEVICE

Robert M. Donohue, Brookline, Mass.

Application December 7, 1933, Serial No. 49,980

Term of patent 14 years

To all whom it may concern:

Be it known that I, ROBERT M. DONOHUE, a citizen of the United States, and a resident of Brookline, in the county of Norfolk and State of Massachusetts, have invented a new, original, and ornamental Design for a Portable Cooling System Cleaning Device, of which the following is a specification, reference being had to the accompanying drawings, forming part thereof.

Referring to the drawings:

Fig. 1 is a side elevation of a portable cooling

system cleaning device showing my new design; Fig. 2 is a top plan view of said device; Fig. 3 is an end elevation of said device; and Fig. 4 is a side perspective view of said device.

I claim:

The ornamental design for a portable cooling system cleaning device, substantially as shown.

In witness whereof, I hereunto subscribe my name this 4th day of December, A. D. 1933.

ROBERT M. DONOHUE.
